[57] ABSTRACT

A method of manufacturing an oxygen generating chlorate candle including the steps of forming a powder-like candle mixture, supplying the mixture to a cavity, closing the cavity, reducing the dimensions of the cavity by a horizontal pressing operation to form the candle, increasing the dimension of the cavity to release the formed candle from at least some of the side walls of the cavity and removing the candle from the cavity.

CHLORATE CANDLE AND METHOD OF MAKING SAME

BACKGROUND OF THE INVENTION

1. Field of the Invention

This invention relates to chemical oxygen generator cells and to a method of forming the oxygen producing candle portion of the cell by a pressing operation.

2. Description of the Prior Art

Chemical oxygen generating devices are known which incorporate a housing such as a tin plated can which has disposed therein an oxygen producing candle. See for example U.S. Pat. No. 3,736,104 for an oxygen generator cell issued May 29, 1973 to John P. Churchill and Tommy Lewis Thompson, the teachings of which are herein incorporated by reference.

Such cells generally contain a compressed chlorate candle briquette, preferably of the chemical formulation disclosed and claimed in my U.S. Pat. No. 3,702,305, issued Nov. 7, 1972. The briquette generally includes an ignition material cone set in one end of the briquette for initiating burning of the chlorate candle. The material for such cones is disclosed in my U.S. Pat. No. 3,725,156 issued Apr. 3, 1973. The teachings of these patents are herein incorporated by reference.

Although the prior art has generally constructed the candle as a cylindrical mass with the ignition cone attached to or impressed in one end of the cylinder, other shapes have been suggested such as, by way of example, frustoconical. Recently, it has been determined that in order to assure a steady and even rate of oxygen delivery while minimizing heat loss, more complex shapes are required. Such a shape is illustrated in my Patent Application entitled "Oxygen Generator Cell", U.S. Ser. No. 338,448, filed Mar. 6, 1973, the teachings of which are herein incorporated by reference.

The formation of such candles generally begins with the creation of a mixture of the candle material. This material is then formed into the desired shape. The prior art has suggested that the candle can be fabricated by casting, hot compression molding, hot extrusion, or hydrostatic compaction. While modifications of such standard techniques can be utilized in the formation of candles, the majority of the suggested methods, with the exception of compression molding, have the disadvantages of either being unable to produce the complex shaped candles which have been found to be the most advantageous or, they involve expensive procedures not readily usable for the economical mass production of inexpensive, disposable oxygen supplying equipment.

Compression molding, on the other hand, has the advantage of being both fast and inexpensive. Normally, such compression molding involves the use of a shaped cavity and a vertical ram which compresses the material into the shaped cavity. Such systems are not usable with the complex configurations of the above discussed new candle shapes inasmuch as it would be impossible to remove the compressed candles from the cavity.

Horizontal pressing has been suggested. However, the suggested forms of horizontal pressing have merely utilized a dimensioned cavity having a ram moving horizontally therein to compress material received in the cavity. While this increases the ability to create complex forms and to remove the resultant candles from the mold, such systems still require ejection devices and are not readily usable on high volume production

lines. In addition, they have the disadvantage of limiting the ability of the ignition cone to be formed into the candle at the time the candle is pressed.

It would therefore be an advance in the art if a high volume, inexpensive production method could be devised for the manufacture of complex shaped oxygen generating candles. It would be a further advance in the art if such a method could include a means for affixing the ignition cone to the candle at the time of formation of the candle.

SUMMARY

My herein disclosed invention provides such a solution. In the preferred embodiment illustrated, my method includes the use of a horizontal pressing device having a cavity formed between two stationary side walls and two movable side walls, the cavity being open at both vertical ends. Means are provided to close the vertical openings of the cavity.

In the construction of an oxygen generating candle, I began with a mixture of materials for the formation of the candle. This mixture preferably is in granulated, powdered, or slurry form and is introduced to the cavity through the top opening. The bottom opening is closed at the time of introduction of the material. The material is introduced to the cavity to a level slightly below the top of the cavity as defined by the bottom of the top slide. Thereafter, a pre-formed ignition cone is placed in the candle mixture. The top slide is activated to close the top of the cavity and the movable side walls are activated in unison to move the cavity to a point spaced from the slides. Thereafter, the side walls are moved towards one another to reduce the size of the cavity thereby compressing the candle into final shape. Thereafter, the movable side walls are returned to their initial position above the bottom opening and the bottom slide is moved to allow the resultant candle to exit from the cavity.

Such a compression device and method results in the formation of a high quality compressed candle with the ignition cone properly placed.

It is therefore an object of this invention to provide a method of manufacturing oxygen generating candles.

It is another and more specific object of this invention to provide a method of producing complex shaped oxygen generating candles by compression molding.

It is another and more important object of this invention to provide a method and apparatus for the production of chlorate candles by compression molding in a die cavity from a candle mixture introduced to the cavity in a loose state.

It is another and more important object of this invention to provide a method and apparatus for the production of chlorate candles with ignition cones embedded therein, the ignition cone being embedded in the chlorate candle when the chlorate candle is formed to a final shape in a compression molding process.

It is yet another and more specific object of this invention to provide a method and apparatus for the formation of oxygen producing chlorate candles with embedded igniter cones with involves the steps of filling an oversized die cavity formed between movable walls and stationary walls with a candle mixture, placing an igniter cone in the mixture, closing the cavity, reducing the dimension of the cavity to a final candle size dimension, increasing the size of the cavity and ejecting the formed candle therefrom.

Other objects, features, and advantages of the present invention will be readily apparent from the following description of the preferred embodiments thereof taken in conjunction with the accompanying drawings although variations and modifications may be effected without departing from the spirit and scope of the novel concept of the disclosure.

BRIEF DESCRIPTION OF THE DRAWINGS

FIG. 1 is a perspective partially sectional view of an oxygen generator cell.

FIG. 2 is a perspective view of an oxygen generating candle formed according to this invention.

FIG. 3 is a diagrammatic view, partially in section, of a cavity filling step according to the method and utilizing the apparatus of this invention.

FIG. 4 is a cross-sectional view taken along lines IV-IV of the apparatus of FIG. 3.

FIGS. 5, 6, 7, and 8 are views similar to FIG. 3 illustrating successive sequential steps in the practice of this invention.

FIG. 9 is a cross-sectional view of the finished candle taken along the lines IX-IX of FIG. 8.

DESCRIPTION OF THE PREFERRED EMBODIMENTS

FIG. 1 illustrates an oxygen generating cell 10 as shown and described in my prior U.S. Pat. Application entitled "Oxygen Generator Cell", U.S. Ser. No. 338,458, filed Mar. 6, 1973. The cell includes a cylindrical tin can 11 with top 13 and bottom 14 walls. The top wall 13 has a circular central opening 15 closed by a foil strip 16. An ignition actuator cup 17 depends from the top 13 below the opening 15 and is closed by another foil strip 16b. Below the top and surrounding the ignition actuator cup 17 are discs of ceramic fiber material 18, ceramic fiber mat 19 and a layer of granular sodium peroxide 20. A further ceramic fiber mat 21 underlies the granular layer 20. A tin plated steel baffle 22 underlies the disc 21 and has a pair of diametrically opposed flat legs 24 depending from the end wall 23 of the baffle and terminating in close space relation to the bottom of the can where it may be supported on a mat 25. The portion 23 of the baffle has a central opening 26 which receives a reduced diameter portion of the cup 17. Under the portion 23 of the baffle may be positioned a plurality of mats 27, some of which surround the cup 17 and some of which surround a pellet of first fire material 30 which is positioned atop a central portion of a sodium chlorate candle 31 which has an end face 32 positioned immediately below the lowest mat 27 and the first fire material 30. An igniter cone 33 is impressed into the end 32 of the candle 31.

A plunger pin 35 is received in the cup 17 which may be filled with an igniter fluid such as water. Activation of the plunger pin 35 will pierce the end 36 of the cup 17 and will force the fluid into the first fire material 30 which will initiate activation of the igniter cone 33 and the sodium chlorate candle 31.

As illustrated in FIG. 2 the sodium chlorate candle 31 is a compressed briquette which is formed of a material which will maintain a self-sustaining catalytic decomposition reaction which will liberate oxygen from the material without the addition of additional heat or fuel. The shape of the candle is as disclosed in my aforementioned patent application Ser. No. 338,458, filed Mar. 6, 1973 and has a main elongated hexagonal cross sec-

tion body portion 40 which converges through a tapered portion 41 to about a halfway point between the top and bottom ends of the briquette and from this level adjoining faces on diagonal opposite sides of the hexagon are cut back in triangular flats 43 to terminate in a rectangular base 44 which rests on the mat 25.

The briquette is formed from a formulation such as that set forth in my aforesaid U.S. Pat. No. 3,702,305 which is preferably initially prepared as a powder, granular mixture, or slurry, hereinafter referred to as a powder. The powder mixture must be compressed under high pressure to form the briquette and, it is desirable, that the pressure be substantially uniform in all sections of the briquette to provide a compacted finished product which will burn evenly to release a continuous amount of oxygen. Of course it is to be understood that other configurations can be created where it is desired, for example, to initially produce a high flow rate of oxygen which thereafter tapers to a lesser rate or vice versa.

According to this invention the briquette 31 is formed by horizontal pressing. It is to be understood that the term horizontal pressing is herein used to refer to pressing from the long sides of the briquette as opposed to pressing from the top and/or bottom ends of the briquette.

As best shown in FIGS. 3 and 4, the pressing is done in a press apparatus which includes movable rams 50 and 51 disposed opposite one another. The rams are received between top and bottom chamber defining members 52 and 53 each of which has an opening 54 and 55 therethrough. The openings 54 and 55 are closable by top and bottom slide members 56 and 57. Side walls 58 and 59 close the area to either side of the rams 50 and 51. Therefore, when the rams are spaced apart as illustrated in FIG. 3 a chamber 60 is defined between the opposed surfaces 61 of ram 51 and 62 of ram 50, the inside surfaces 63 of side wall 58 and 64 of side wall 59 and the combination of the members 52 and 53 and the slides 56 and 57. It will be understood that the rams are movable and are acted upon mechanically or hydraulically and that the slides are also movable and are actuated by external motive means.

The top portions 70 of the side of the rams 50 and 41 may be angled inwardly with corresponding angulations of the side walls 58 and 59 and the side faces 61 and 62 of the rams 50 and 51 may be configured with angled top and bottom portions so as to provide the final briquette shape as illustrated in FIG. 2 or some other desired shape.

The rams 50 and 51 are independently movable towards and away from one another and are initially positionable such that the cavity 60 underlies the opening 54 and overlies the opening 55. Because the rams are individually movable, the initial cavity 60a as illustrated in FIG. 3 can be formed oversized with respect to the final briquette size.

The powder mixture 70 is introduced to the cavity 60a through the opening 54 with the slide 57 closed. It will be noted that in the embodiment illustrated the top surface 71 of the slide 57 and the bottom surface 72 of the slide 56 are level with the corresponding surfaces of the members 52 and 53 which are continuous except for the slides and the openings 54 and 55. The powder material is introduced to the cavity to a level below the bottom surface 72 of the slide 56 while the rams 50 and 51 are spaced apart from one another a distance such

that the total amount of powder material introduced to the oversized cavity 60a is equal to the desired weight of powder in the finished briquette. Thereafter, as illustrated in FIG. 5, the ignition cone 33 is placed in the powder 70 through the opening 54. The ignition cone may be placed by any means such as by hand or automated machinery or the like and is pressed into the powder so that the top 33a of the cone lies below the bottom surface 72 of the slide 56. Thereafter, as illustrated in FIG. 6, the slide 56 is closed closing the opening 54 and the rams 50 and 51 are moved to one side of the openings 54 and 55 where the cavity 60b will be defined between the opposed faces of the rams 50 and 51 and the opposed surfaces of the members 52 and 53 and the opposed faces of the side walls 58 and 59. It is to be understood that this movement of the rams is an equal movement where both rams move the same distance maintaining the cavity 60b at substantially the same size as the cavity 60a with the top closed. Further, it will be understood that movement of the rams is in a preferred embodiment only and that in other embodiments, the slides 56 and 57 could be constructed of a sufficiently heavy material to withstand the pressures generated during the pressing operation. In such an instance then the pressing can take place between the rams in the area under the slides and in alignment with the openings 54 and 55.

As illustrated in FIG. 7 after the movement illustrated in FIG. 6, the rams are moved towards one another to reduce the cavity 60b to a final briquette size 60c compressing the powder material 70 to the desired density. It will be appreciated that the ignition cone 33 will be maintained in the center portion of the briquette by the pressure generated by the ram and will be firmly embedded in the briquette during the pressure formation of the briquette. Further, because of the cone shape, the ignition cone 33 will remain at the top of the final briquette.

Although in the preferred embodiment the rams 50 and 51 cooperate by moving towards one another to form the briquette, in other embodiments one of the rams could remain stationary during the pressing operation while the other ram moves toward it to reduce the cavity to the size 60c.

Thereafter, the rams are moved in unison to a position above the opening 55. At this point as illustrated in FIG. 8, the rams are separated from one another to create a cavity 60d which is larger than the briquette 31, thereby releasing the briquette from at least one ram wall, any adhesion to the side walls or members 52 and 53 being broken by movement of the cavity 60c to the position above the opening 55. In this manner, when the slide 57 is moved to open the opening 55, the briquette 31 will fall from the cavity 60d.

As the briquette 31 is removed from the pressing apparatus, it will be formed into the final desired shape as illustrated in FIG. 2, by reason of having been pressed against the side walls 63, 64, the top and bottom surfaces of the members 52 and 53 and the opposed faces of the rams. By forming the triangular shaped portions 43 of the briquette by the opposed faces of the rams, and thereafter by separating the rams as illustrated in FIG. 8, it is assured that the final shaped briquette can be removed through the opening 55.

It will be appreciated that because the initial cavity 60a is substantially larger than the finished briquette, the finished briquette can be made with the hexagonal

central portion 40 as illustrated in FIG. 9 while still maintaining a proper density.

Thus, my invention envisions the use of opposed movable rams which are received between stationary side wall portions to create a four walled cavity with two of the opposed walls defined by opposed faces of the rams. The cavity has top and bottom walls formed either by the movable slides 56 and 57 or by the stationary surfaces of the members 52 and 53 to one side of the openings 54 and 55. The dimensions of a cavity formed between the ram faces are changeable by movement of the rams. In the preferred embodiment, both rams are movable to allow the cavity to be shifted to the area underlying the members 52 and 53 spaced to the side of the opening and to ensure that the briquette will be easily removable from the cavity when it is in finished form. In an alternative embodiment, the apparatus may form the final briquette by compressing the material in a cavity area intermediate the openings 54 and 55 which is closed by heavy slides 56 and 57. In other embodiments, the openings 54 and 55 may be offset from one another with the pressing being done in alignment with one or the other opening which may be closed by a heavy slide or in an area intermediate the openings.

Sequentially, my method comprises the steps of forming a cavity having an opening thereto, the cavity having a first dimension and location, supplying a measured quantity of powder mixture to the cavity through the opening, inserting an ignition cone into the cavity through the opening at the top of the powder mixture, closing the opening to the cavity, shifting the cavity to a location spaced from the first location, reducing the size of the cavity to a second dimension less than the first dimension to compress the powder material to a finished formed briquette, shifting the cavity back to the first position, increasing the size of the cavity from the second dimension and opening the cavity to eject the finished briquette with embedded ignition cone. Of course, it will be understood that the shifting of the cavity can be eliminated when using the embodiment with the heavier slides 56 and 57.

Although minor modifications might be suggested by those versed in the art, it should be understood that I wish to employ within the scope of the patent warranted herein all such modifications as reasonably and properly come within the scope of my contribution to the art.

I claim as my invention:

1. The method of manufacturing a compressed oxygen producing candle by horizontal compression molding in a fixture which comprises steps of:

providing a fixture with top, bottom and two opposed stationary side walls, and two opposed horizontally movable second walls positioned between the stationary walls, the side walls being spaced from one another, and the second walls being spaced from one another defining a cavity between the side and second walls, the opposed surfaces of the second walls being contoured to provide non-continuously planar die surfaces,

providing top and bottom openings through fixture portions connecting the side walls above and below the second walls, the openings communicating to said cavity defined by said walls, slide closures at said top and bottom openings for closing said open-

ings, the cavity having a first size and being located at a first position aligned with the top opening; positioning the bottom closure in a bottom opening closed position, positioning the top slide in an open position with the top opening communicating with the cavity, substantially filling the cavity with a powder material through the top opening which, when compressed, forms an oxygen producing candle, placing an ignition cone in the cavity, through the top opening, 10 partially submerging the ignition cone in the powder metal, moving the top slide to a closed position closing the top opening, shifting the cavity to a second cavity position remote from the first cavity position and remote from the top and bottom openings by horizontal movement of the second walls, reducing the size of the cavity to a second size less than the first size while compressing the powder material to form a compressed candle with an ignition cone embedded in the candle at the top 20 thereof by horizontal movement of the second walls, increasing the cavity to a third size larger than the second size and shifting the cavity back to the first position by horizontal movement of the second walls, moving the bottom slide to an open 25 position communicating the bottom opening with the cavity, and removing the compressed candle from the cavity through the bottom openings.

2. The method of manufacturing a compressed oxygen producing candle by horizontal compression molding in a fixture which comprises steps of:

providing a fixture with top, bottom and two opposed stationary side walls, and two opposed horizontally movable second walls positioned between the stationary walls, the side walls being spaced from one 35

another, and the second walls being spaced from one another deferring a cavity between the side and second walls, the opposed surfaces of the second walls being contoured to provide non-continuously planar die surfaces,

providing top and bottom openings through fixture portions connecting the side walls above and below the second walls, the openings communicating to said cavity defined by said walls, slide closures at said top and bottom openings for closing said openings, the cavity having a first size and being located at a first position aligned with the top opening; positioning the bottom closure in a bottom opening closed position,

positioning the top slide in an open position with the top opening communicating with the cavity, substantially filling the cavity with a powder material through the top opening which, when compressed, forms an oxygen producing candle, placing an ignition cone in the cavity, through the top opening, partially submerging the ignition cone in the powder metal, moving the top slide to a closed position closing the top opening, reducing the size of the cavity to a second size less than the first size while compressing the powder material to form a compressed candle with an ignition cone embedded in the candle at the top thereof by horizontal movement of the second walls, increasing the cavity to a third size larger than the second size, moving the bottom slide to an open position communicating the bottom opening with the cavity, and removing the compressed candle from the cavity through the bottom openings.

* * * * *
